UNITED STATES PATENT OFFICE.

BUTLER AMES, OF LOWELL, MASSACHUSETTS.

MAGNETIC RAZOR.

1,299,096.

Specification of Letters Patent.

Patented Apr. 1, 1919.

Application filed June 9, 1917. Serial No. 173,841.

To all whom it may concern:

Be it known that I, BUTLER AMES, a citizen of the United States of America, and resident of Lowell, in the county of Middlesex and State of Massachusetts, have invented new and useful Improvements in Magnetic Razors, of which the following is a specification.

This invention relates to cutting devices and more particularly to safety razors of the type disclosed in my prior Patent No. 1,192,367.

Safety razors of the general character of the subject-matter of the present application have usually comprised a guard member and a cap member disposed over the guard member for holding a blade in position between the two members. Screw means or some other mechanical mechanism has usually been employed for detachably holding the parts together while the device is being used. Such mechanism has involved a substantial increase in cost of manufacture, it has involved considerable inconvenience in use, and it has involved screw-threads and the like, which have rendered the devices difficult to clean and therefore more or less unsanitary.

The principal objects of the present invention are to overcome the above difficulties and to produce a device which may be simply and cheaply constructed, which is exceedingly convenient in operation, requiring no manipulation of screws or other mechanism in attaching and detaching the parts to and from each other, and which is wholly sanitary. Other objects of the invention, such as improving the coöperative relationship of the guard, handle and other parts with respect to each other, will be apparent from the following description and the accompanying drawings, in which,—

Figure 1 is a side elevation of one embodiment of the invention;

Fig. 2 is a central longitudinal cross-section of the device, showing parts in elevation;

Fig. 3 is a view similar to Fig. 2, showing the parts in detached relationship;

Fig. 4 is an end elevation of the device;

Fig. 5 is a top plan view of the device with the cap and blade removed; and

Fig. 6 is a top plan view of the device with the cap and blade in position.

The most essential part of my improved

device comprises magnet means, and an essential characteristic of the magnet means involves one or more poles for holding the razor blade or other cutting device in position. While a single pole will accomplish this result, I preferably employ a magnet having two poles in spaced relationship. The preferred type of magnet means comprises a U-magnet, as shown at 1 in the figures, the U-magnet 1 having pole faces 2 and 3 disposed substantially in the same plane. In order to support the blade 4 in position in the device I provide a base member 6 which is also preferably constructed to function as a guard member, in which event teeth 5 or other suitable means are provided along one side of the member and preferably along both sides of the member as illustrated in the drawings, so that a double edged blade may be employed, the teeth 5 extending outwardly somewhat beyond the edges of the blade, as shown in Fig. 6.

Another cardinal feature of the invention comprises means for rigidly mounting the guard member 6 upon the magnet 1 and at the same time permitting the ready withdrawal of the guard member and mounting means from the magnet. The preferred embodiment of the mounting means, according to the present invention, comprises pole pieces 7 adapted to fit over the ends of the U-magnet and into spaced openings 8 in the guard 6, the pole pieces being formed of steel or other magnetic material. While the pole pieces 7 may, if desired, be fixedly secured in the guard member 6, I preferably fit them tightly in the openings 8 so that the connection is permanent. The connection between the pole pieces 7 and the magnet 1 is preferably a detachable connection so that the pole pieces and guard may be removed for the purpose of cleaning the device, replacing damaged parts, or having the magnet 1 remagnetized. In order yieldingly to hold the pole pieces upon the magnet I preferably provide a series of depending lips 9 on the bottom of each pole piece, these lips being somewhat flexible and fitting snugly around the magnet so as yieldingly to grip the poles of the magnet when the pole pieces are mounted thereon.

The blade 4 is preferably surmounted by a cap member 11, and in order to prevent lateral movement of the guard member, cap 11

member and blade relatively to each other, projections are preferably provided upon one of the said members, recesses being provided in the other member in alignment with the projections, and in the particular embodiment of the invention illustrated in the drawings, the projections comprise pins 12 fitting in axial openings in the pole pieces 9 and being adapted to extend through openings in the blade 4 into recesses 13 in the cap 11. The cap 11 and blade 4 are adapted to be held in position on the guard member 6 by magnetic flux flowing from one pole of the magnet to the other pole through the blade and cap, as will be hereinafter more fully described, and to avoid diminution of this magnetic action the pins 12 are preferably made of non-magnetic material, since if the pins were of magnetic material a large number of lines of flux would flow therethrough from the magnet to the cap member, and inasmuch as many of these lines of force would pass from the pins in a substantially radial direction to the cylindrical walls of the recesses 13, the magnetic attraction would be substantially decreased owing to the fact that the radial lines of force would not serve in appreciable measure to prevent the displacement of the cap member from the device. When forming the pins 12 of non-magnetic material it is essential that the face of each of the pole pieces 7 be maintained of at least the same area as the cross-sectional area of the magnet, and to accomplish this I preferably flare the pole pieces outwardly toward their outer faces. In this way the pole pieces 7 do not afford a higher reluctance than any other part of the magnetic circuit.

40 To attain the greatest efficiency it is essential that as much as possible of the magnetic flux produced by the magnet should be caused to flow through the blade 4 and cap 11; conversely, it is essential that as little as possible of the flux be shunted from the blade and cap member. I therefore so construct the guard member 6 that no appreciable amount of flux is shunted therethrough between the pole pieces. This may be accomplished in a number of ways, as by making the guard member very thin or by making it of non-magnetic material, but in the preferred form of the present invention the guard member 6 is made of brass or other non-magnetic material.

45 The operation of the apparatus is as follows: The guard member 6, the pole pieces 7 and the pins 12 are preferably fixedly secured together as shown in Fig. 3 and when so constructed this unitary structure is fitted over the ends of the magnet 1, the depending flanges 9 gripping the magnet and yieldingly holding the parts in position. The blade 4 is then placed on the guard member 65 with the pins 12 projecting through the

openings in the blade as shown most clearly in Fig. 2. If the blade is relatively thin, as shown in the drawings, the magnetic flux flowing through it when in the described position is only sufficient to hold it lightly 70 in position. However, by increasing the thickness of the blade throughout the central portion, as by making the upper surface of the blade transversely convex, sufficient flux may be caused to flow through the blade to 75 hold it in position while the device is in use, in which event the cap member 11 is rendered unnecessary. However, I preferably employ a thin blade as shown in the drawings and when employing such a blade the 80 cap member is placed over the blade, with the pins 12 projecting into the recesses 13, as most clearly shown in Fig. 2. With the blade and cap in position on the guard member, magnetic flux flows from one pole, for 85 example pole 2, through the surrounding pole piece 7, from the face of the pole piece into the blade and cap, thence through the blade and cap to the face of the other pole piece, and thence through the other pole 90 piece into the other pole of the magnet. When the magnetic circuit is thus substantially closed the parts are tightly held together and the device may be used in the ordinary manner, the U-magnet 1 serving 95 as a convenient handle. To disassemble the device, the cap member may be removed by gripping it at the opposite ends, where it projects over the guard member 6, and by either pulling directly outwardly or by first 100 tipping one end of the member upwardly so as to break the magnetic circuit. Inasmuch as the magnetism has a beneficial effect on the blade, the blade is preferably left in position on the pole pieces while the 105 device is not in use; and in order to conserve the magnetism of the magnet the cap member 11 is also preferably kept in position on the blade and guard when the device is not in use.

110 Certain modified embodiments of the present invention are disclosed and claimed in my copending applications Sr. No. 173,110, filed June 6, 1917, and Sr. No. 173,923, filed June 11, 1917, and I hereby make reference 115 to these applications as showing variations in the manner of applying the invention, some of which are common to the embodiment disclosed in the present invention.

116 I claim:—

120 1. A razor comprising magnet means having an elongate member of magnetic material, and a magnetic pole piece fitting over one end of the elongate member, the pole piece being adapted to maintain a cutting blade in position thereon by the magnetic action of the magnet means.

125 2. A razor comprising a base member having an opening therethrough, magnet means comprising an elongate member of 130

- 1 magnetic material, and a magnetic pole piece adapted to fit over one end of the elongate member and into said opening.
- 2 3. A razor comprising magnet means comprising an elongate member of magnetic material, a magnetic pole piece adapted to be detachably mounted on the end of the elongate member, and means for yieldingly holding the pole piece in position 10 on the said member.
- 3 4. A razor comprising magnet means comprising an elongate member of magnetic material, and magnetic pole-piece means adapted to be detachably mounted on the 15 end of the elongate member, one of said means being adapted yieldingly to engage the other means thereby to maintain the pole-piece means in position on the magnet means.
- 4 5. A safety razor comprising guard means having spaced openings therethrough, an elongate magnet member having its ends disposed at said openings, and magnetic pole pieces fitting over the said ends and into 20 the said openings.
- 5 6. A safety razor comprising guard means having spaced openings therethrough, an elongate magnet member having its ends disposed at said openings, magnetic pole pieces 25 fitting over said ends and into said openings, a magnetic cap member disposed above the guard member, one of said members having recesses therein, and non-magnetic members extending from the other of said members 30 into said recesses, whereby a cutting blade may be maintained in position between the guard means and cap member by the magnetic action of the magnet member upon the cap member.
- 6 7. A safety razor comprising a non-mag- 35
- netic guard member having spaced openings therethrough, a U-magnet having its ends disposed at said openings, magnetic pole pieces fitting over the ends of the U-magnet and into the said openings, and a 45 magnetic cap member disposed above the guard member.
- 7 8. A safety razor comprising a non-magnetic guard member having spaced openings therethrough, a U-magnet having its ends 50 disposed at said openings, magnetic pole pieces mounted on the ends of the U-magnet and extending into said openings, a cap member disposed on the side of the guard member opposite to the U-magnet, the pole 55 pieces and cap member having alined openings, and non-magnetic pins disposed in the openings to prevent lateral movement of the cap member relatively to the guard member.
- 8 9. A safety razor comprising a non-magnetic guard member having spaced openings therethrough, a U-magnet having its ends 60 disposed at said openings, magnetic pole pieces mounted on the ends of the U-magnet 65 and extending into said openings, a cap member disposed on the side of the guard member opposite to the U-magnet, the pole pieces and cap member having alined openings, and non-magnetic pins disposed in the 70 openings to prevent lateral movement of the cap member relatively to the guard member, the area of the pole piece faces being at least substantially equal to the cross-sectional area of the U-magnet notwithstanding 75 the reduction in area produced by said openings therein.

Signed by me at Lowell, Massachusetts,
this 2nd day of June, 1917.

BUTLER AMES.
